UNITED STATES PATENT OFFICE.

STEVE STARCOVIC, OF SEDRO WOOLLEY, WASHINGTON.

FASTENER FOR SHOES AND THE LIKE.

1,190,033.

Specification of Letters Patent.

Patented July 4, 1916.

Application filed January 11, 1916. Serial No. 71,521.

To all whom it may concern:

Be it known that I, STEVE STARCOVIC, a citizen of the United States, residing at Sedro Woolley, in the county of Skagit, 5 State of Washington, have invented a new and useful Fastener for Shoes and the like; and I do hereby declare the following to be a full, clear, and exact description of the invention, such as will enable others skilled 10 in the art to which it appertains to make and use the same.

This invention relates to the art of fasteners, and particularly to an improved fastener especially adapted for use upon shoes 15 and the like, for instance heavy overshoes of the Blucher type.

One of the objects of the invention is the provision of a fastener comprising two plates designed to be embedded in the opposite portions of the upper of the shoe, one 20 of which plates being provided with apertures to receive the hollow lugs of the other plate, in combination with a pair of pivoted dogs, to engage recesses of the lugs to hold 25 the lugs in said apertures, thereby fastening the two plates together.

Another object of the invention is the provision of a sliding plunger or plate which is spring tensioned axially and connected to the levers for holding them out 30 of engagement with said notches.

Another object of the invention is to construct this plate of yieldable material and provide the same with an enlargement at 35 one end, which is designed to be pressed through an opening in the plate, which holds the plunger outwardly from the plate with the openings, thereby holding the levers in the notches of the lugs.

40 In practical fields the details of construction may necessitate alterations, falling within the scope of what is claimed.

The invention comprises further features and combination of parts, as hereinafter set 45 forth, shown in the drawings and claimed.

In the drawings: Figure 1 is a view in elevation, showing the fastener as applied to an upper of a shoe, showing the levers out of engagement with the notches of said 50 lugs which extend through the opening of one of the plates. Fig. 2 is a similar view showing the levers in engagement with the notches of said lugs. Fig. 3 is a sectional view on line 3—3 of Fig. 1. Fig. 4 is a sectional view on line 4—4 of Fig. 2. Fig. 5 55 is a detail view of one of the locking levers.

Referring more especially to the drawings, 1 designates a shoe, and 2 and 3 denote the plates, which are fastened to the opposite sides 4 and 5 of the upper of the 60 shoe, particularly an overshoe of the Blucher type. The plate 2 is provided with a pair of spaced apertures 6, and pivoted to the plate as at 7 is a pair of levers 8 having their outer end portions 65 curved as shown at 9. The inner ends of the levers are provided with adjacent reduced extensions 11, which are passed through an aperture 13 of a slide bar 14, which extensions are bent over and laterally 70 from each other, so as to pivotally connect the inner ends of the lever to the slide bar or plate. The slide bar or plate has spring means 12 connected to one end thereof, and which spring means in turn is connected to 75 one edge of the plate 2, thereby tensioning the slide plate, so as to hold the outer curved portions of the levers from the apertures in the plate 2. The plate 3 is provided with a pair of spaced hollow lugs 13^a, which 80 are designed to pass through the apertures of the plate 2, so as to permit the curved portions of the levers to engage the notches 14^a of said lugs, thereby holding the lugs in the apertures, and securely connecting 85 the two plates 2 and 3 for holding the opposite sides of the upper connected. One end of the slide bar (which is constructed of spring or yieldable material) is provided with an enlargement 15, which extends 90 through an opening 16 in the plate 2. However, when it is desired to cause the curved portions of the levers to more firmly engage the notches of the lug, the enlargement of the slide bar is pushed outwardly 95 through the opening 16 in the plate 2, thereby slightly bending the slide bar to hold the levers in engagements with the notches. When connecting the opposite sides of the upper, the plate 2 is arranged 100 to overlie the plate 3, the hollow lug of the plate 3 in this case will pass through the apertures of the plate 2, and owing to the lugs being beveled off as shown at 17, they will slip by the curved parts of the 105 levers, thereby permitting the levers to engage said notches.

The invention having been set forth, what is claimed as new and useful is:

In combination, a pair of overlapping 110 plates embedded in opposite portions of an upper of a shoe, one of said plates hav-

ing a pair of spaced apertures, the other plate having a pair of spaced lugs adapted to enter the apertures, and provided with notches, a pair of pivoted levers having 5 curved portions to simultaneously engage, said notches, to hold the lugs in said apertures, and means to yieldably hold the curved portions of the lever in engagement with said notches, a slide bar connected to 10 said yieldable means and having pivotal connections with the inner ends of said levers, one end of the slide bar having an enlargement, the plate having the levers having an opening through which the en- 15 larged end of the slide bar engages, said

enlargement adapted to be pushed outwardly through the opening and partially engage one end of the opening, thereby partially bending the slide bar to securely hold the curved portions of the levers in 20 engagement with the notches.

In testimony whereof I have signed my name to this specification in the presence of subscribing witnesses.

STEVE STARCOVIC.
